UNITED STATES PATENT OFFICE.

GEORGE D. REAGAN, OF OKLAHOMA CITY, OKLAHOMA.

HOLLOW BUILDING UNIT.

Application filed February 25, 1926. Serial No. 90,642.

My present invention is a novel and improved form of hollow building tile, brick or unit, of the type illustrated in my prior Patent 1,495,439, having capacity for fracturable sub-divisions, and the resulting wall structure therefrom. I have illustrated various other modifications of my novel building units or blocks, in co-pending applications, viz., Serial No. 89,621, filed February 20, 10 Serial No. 93,698, filed March 10, 1926, and Serial No. 93,699, filed March 10, 1926.

In my development of the art of hollow brick or tile and wall structures, I have devised several forms of hollow building unit, 15 having a plurality of pairs of interior webs, giving a capacity for fracturable sub-divisions, while still preserving a usable building unit in the part or parts thus broken and sub-divided. In the present form of my invention, I have herein illustrated a peculiarly desirable and advantageous structure 20 of hollow block or tile, combining with the features of the interior pairs of webs permitting fracture of the connections therebetween, a block having different forms of 25 outer wall faces. Important advantages in the present invention consist in the facility of breaking the block, providing a block with relatively thick load carrying, fire resisting outer faces, together with air spaces or voids in these wall faces, which, however, will not prevent their utilization as mortar beds throughout the entire thickness of the 30 wall face; great facility in laying up the wall structure by reason of the size and area of the block; the important advantage of interrupting the horizontal mortar beds by hollow air spaces; and the further advantage of enabling a relatively broad mortar bed— 35 or a plurality of broad mortar beds—to be employed, giving great load-carrying capacity and compressive strength.

Furthermore, my present form of block is extremely simple to manufacture, enabling a 40 column of clay material to be forced out through a die to form the same, and wire cut in any desired width or lengths. Thus I 45 preferably form my entire block of substantially brick-size in its outer face, while it 50 may be equally well cut in cube form or longer. A desirable dimension as for a ten inch wall would give the tile practically of ten by ten width and depth, and when cut for substantially brick-size appearance would be approximately 3" in height.

I have illustrated in the attached draw-

ings, several modified forms, each having the capacity for sub-division into lesser building units, of which the original complete form in cross-section is a multiple, and each 60 affording the desirable advantages of double hollow wall faces, giving a broad mortar bed spanning the small hollows, together with an interruption of the horizontal mortar bed, where desired, and also ready break- 65 ing or fracturability.

I may also form the blocks of the present invention with one or more kerfs or predetermined corners which may be either left in the face of the wall and filled with mortar, 70 or will facilitate mortar receiving on the inside of the wall. Preferably such kerfs are substantially like those shown in my prior and copending application Ser. No. 674,289, filed November 12, 1923, wherein I 75 claim broadly this feature of an offset web around these kerfs.

Further novel features, combinations and advantages will be hereinafter more fully pointed out and claimed. 80

Referring to the drawings illustrating preferred embodiments of the invention,

Fig. 1 is a partial perspective view of a wall structure;

Fig. 2 is a perspective view of the block shown in Fig. 1, with a quarter broken away;

Fig. 3 illustrating a block with a half broken;

Fig. 4 illustrates a quarter sub-division which is still useful as a building unit; 90

Fig. 5 is a view of an oblong form of block.

Referring to the block illustrated in Figs. 1, 2, 3 and 4 this block or building unit gives capacity for ready and interchangeable fracturing in either cross diameter. The block or unit, therefore, is made up in original form, with practically four equal quarter sections, united by fracturable connections. Each quarter section also has preferably at 100 least one outer face made of two webs with a relatively small void therebetween, thus giving capacity for broad mortar bed, which would cover both webs and span the relatively small void therebetween. Designating 105 this block generally as 1, it is formed with the outer faces of each quarter comprising the face 2 and adjacent web 3, with a small void 4 therebetween. Along the adjacent front face 2 is a single wall 5 in each section, and with the interior webs 8 and 9, constituting one wall of the interior pair of

cross webs through which the block is broken into halves or quarters. Thus the webs or walls 3, 5, 8 and 9 of each quarter enclose a relatively large opening or void 10. The entire block is thus composed of fracturable quarters along the lines of the double interior cross-webs 8 and 9, being connected at the center by one or more fracturable connections 12, and at or near the faces by fracturable connections, preferably offset as illustrated at 15, thus permitting the formation of kerfs 16 having smooth predetermined corners formed thereon. The center connecting web 12 and the smooth corner construction of the kerfs, is substantially identical with this feature as illustrated in my prior and copending application Ser. No. 89,621, filed February 20, 1926. It will be readily appreciated that this form embodies the advantages of the double pairs of interior cross-webs, giving relatively long fracturable voids as designated at 20 and 21.

When built into a wall structure as shown in Fig. 1, the double web portions are preferably positioned in the outer wall face, or in parallelism to receive the comparatively broad mortar beds 25, 25, the mortar readily spanning the small voids 4 and simply "keying in" same, while thus covering the two adjacent webs 2 and 3. The block 1 is preferably of suitable area to span the width of the wall, as shown, and a half block 30, as illustrated in Fig. 3 and at the corner of the top course shown in Fig. 1, can be readily fractured and built in with the wall to stagger joints on the full blocks.

The kerfs 16 are of sufficient and proper width and depth to receive the mortar strips 31 to correspond with the real mortar joints 40 at 32 between the half tile 30 and the block 1, thus giving the outer wall appearance of substantially brick bonding. If desired, these kerfs may be left open, simulating the appearance of a raked out joint.

45 While I preferably utilize separated mortar beds—as shown at the right in Fig. 1—to provide moistureproofness, the large air spaces 10 thus interrupting each horizontal mortar course, yet I may equally advantageously employ a practically solid mortar bed as shown at 35, at the left of Fig. 1. Thus, where greater strength is desired, or where half blocks or quarter sections may be employed, it is sometimes desirable to increase the mortar bed, in which case the entire web strength of the wall structure is utilized by mortar coverings, leaving only the hollow interior air openings 10. Thus the small voids in the wall faces or between the double webs of the wall face, are sealed at each mortar course, whereas the large voids 10 are preferably open throughout the height of a story or of the wall. Insulating material, piping, wiring, etc., may be conducted through any of these air spaces,

thereby adding the provision of a cold proof, heat proof and moistureproof wall structure.

In Fig. 5 a still further oblong form of block 70 is shown, constructed preferably for longitudinal fracturing into two relatively long rectangular building blocks and of any height or width desired. For this purpose the kerfs 16 are preferably applied and with the small fracturable cross-webs 71, 71, at each end, and 72 in the approximate middle, it can be readily broken, while the double pair of interior cross-webs 73 and 74 permit lateral fracturing where desired. In all the forms, as herein illustrated, I employ the feature of double interior pairs of cross-webs, with fracturable connections therebetween, thus resulting in the sub-division of usable building members from the entire unit or block. Furthermore, with the building unit thus subdivided—where desired at 80 beams, windows, piers, walls, or around pipes or the like, I prevent all waste by utilizing the resultant sections, and even when thus sub-divided, the sections broken can be repositioned in the wall with perfect 85 facility and interlocking where desired. The small broken fracturable connections 12, 15, etc., are of such slight extent that they will readily be buried within and covered by the adjacent mortar joint, permitting use of 90 the half and quarter sections interchangeably, horizontally or vertically, so far as the voids are concerned. All the different forms of blocks may be of any appropriate size or dimension, and of cubical or rectangular 100 extent, capable of being made in an economical die machine and wire cut to length. In fact the wire cutting cross-wise of the line of travel of the column of clay material is a desirable feature, as such wire cutting 105 will usually partially close the small voids 4 in the wall faces, thereby preventing mortar from falling therein—other than slightly extending downwardly to key the walls and hence affording the united extent 110 of a broad mortar base of both webs and the area of the void 4. The blocks are used interchangeably, interlock completely, and fracture into sub-divisions easily.

115 My invention is further described and defined in the form of claims as follows:

1. A rectangular hollow building tile of the kind described, comprising a plurality of separable units, each unit being defined at the exterior faces of said tile by kerfs formed by offset transverse webs uniting said units and a single connecting web located centrally of said tile. 120

2. A rectangular hollow building tile having a plurality of large voids defined by the outer walls on one side thereof, and on the other sides by webs having smaller voids therein, one pair of said webs being connected at their center by a single transverse web, and terminating at the outer walls at 125 130 136

fracturable connections, said fracturable whereby said tile may be divided into a plurality of smaller tiles, each having three of connections comprising offset webs, another pair of said webs being divided by the first pair of webs and terminating at the outer 5 walls at similar fracturable connections, all of said fracturable connections having formed predetermined corner structures.

In testimony whereof, I have signed my name to this specification.

GEORGE D. REAGAN.
